United States Patent Office

Des. 178,478
Patented Aug. 7, 1956

178,478

CYCLE HANDLEBAR OR SIMILAR ARTICLE

Norman G. Wintermantel, Palos Heights, Ill., assignor
to Junior Toy Corporation, a corporation of Delaware

Application October 5, 1954, Serial No. 32,552

Term of patent 14 years

(Cl. D34—15)

Fig. 1 is a side elevational view of a cycle handlebar or similar article, showing my new design;

Fig. 2 is a side perspective view thereof; and

Fig. 3 is a top perspective view thereof.

The dominant features of my new design are shown in solid lines in the drawing.

I claim:

The ornamental design for a cycle handlebar or similar article, as shown and described.
